UNITED STATES PATENT OFFICE.

ERNEST H. JACOBS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

CHOKE-COIL MOUNTING.

1,274,555.

Specification of Letters Patent.

Patented Aug. 6, 1918.

Application filed April 29, 1918. Serial No. 231,549.

To all whom it may concern:

Be it known that I, ERNEST H. JACOBS, a citizen of the United States, residing at Chicago, in the county of Cook and State of Illinois, have invented a certain new and useful Improvement in Choke-Coil Mountings, of which the following is a full, clear, concise, and exact description, reference being had to the accompanying drawings, forming 10 a part of this specification.

The present invention relates to choke coils and more particularly to a mounting for such coils.

Choke coils are usually inserted in transmission lines at a point where the same connect with apparatus such as transformers, etc. The choke coil is an air inductance having low ohmic resistance and low reactance for normal frequency. For disturbances on the line such as are caused by lightning or surges which produce alternations of current flow of a very high frequency or of a steep wave front, the choke coil presents a very large reactance which 20 hinders the passage of such disturbance through the same. A lightning arrester is usually employed in connection with the choke coil to relieve the disturbance.

Choke coils are usually made of bare wire 30 wound into an open helix and supported at their ends. Due to the necessity of preventing contact between turns, due to the force developed tending to move the turns and due to the lack of rigidity, as well as lack of 35 tensile strength, it has been a very awkward matter to mount a choke coil in any acceptable manner.

My invention aims to overcome the difficulty heretofore experienced in mounting 40 choke coils.

More specific objects of my invention are:

To provide an adjustable choke coil mounting adapted to receive coils of different lengths, whereby the inductance of the 45 unit may be readily varied;

To provide a universal and interchangeable arrangement of parts whereby the insulation of the coil mounting may be increased or decreased as desired; and

50 To provide a choke coil mounting adaptable to indoor or outdoor service and which will be simple, compact, rugged and inexpensive to manufacture.

This mounting is composed of certain im-

proved fittings in combination with universal insulators and adjustable supporting means therefor, all coöperating to produce a choke coil mounting having the above characteristics. To the end of making the choke coils readily interchangeable, I have 55 provided novel brackets for supporting the same which have an adjustable clamping feature capable of clamping to coils of different gage wire. To the end of making the insulating capacity of the mounting adjustable I have employed universal insulators and universal clamps for attachment thereto, these insulators being readily interchangeable to facilitate substitution of longer or shorter insulators. 60

The present fittings and insulators are standardized and are interchangeable with the fittings and insulators described in my copending application, Serial No. 231,548 filed on April 29, 1918. 70

A flexibility of assemblage is obtained through the use of the universal fittings and clamps, which is advantageous for adapting the mounting to an upright, inverted or vertical position. 80

In the accompanying drawings in which I have illustrated one preferred embodiment of my invention—

Figure 1 is a plan view of the choke coil and mounting; 85

Fig. 2 is a side elevation of the same;

Fig. 3 is a detail elevation of the choke coil bracket;

Fig. 4 is a side elevation of the same; and

Fig. 5 is an enlarged fragmentary elevation of one of the clamping arms of the bracket. 90

A supporting structure for the insulators and coil is formed by the two parallel pipes 7-7 which may be independent or comprise 95 part of a frame structure for supporting a plurality of electrical fittings. Two plates 8-8 rest upon the pipes 7 and have integral guiding fingers 9-9 extending laterally from the plates and partly embracing the peripheries of the pipes 7. Both plates are identical and support identical insulator units. 100

Confining the description to the left hand insulator unit, a pair of clamping yokes 11-11 extend transversely of the pipes 7 at each end of the plate 8 and are slung from the plate 8 by bolts 12-12. These bolts 105

- pass through bosses 14 on the yokes 11 and extending ears 15 on the plate 8 and by tightening the same the plate can be clamped at any desired point along the pipe frame 7.
- 5 The ends of the clamping yokes 11 curve up around the peripheries of the pipes 7 to prevent swinging of the yoke and these ends are formed with a reinforcing rib 16.

The insulator 17 has circumferential 10 beads of substantially the same diameter formed in its upper and lower ends. Insulator clamps 18 and 19 engage over these beads, respectively. The insulator 17 is of the petticoat type and is intended for either 15 indoor or outdoor service.

Each of the clamps 18 and 19 is split into 20 two semi-circular bands which are normally held in clamped engagement with the insulator beads by short bolts 24, passing through the ears 25 on the ends of the clamps. Two feet 26 project downwardly and radially from each semi-circular band of the lower clamp 19 and are bolted by bolts 27 to the base plate 8. The lower clamp 19 is 25 thus connected at four points to the base plate 8. I also contemplate cementing a pin of unique form in the lower end of the insulator and releasably attaching it to the clamp 19 to prevent turning or tilting of the 30 insulator. This pin and the particular construction of the lower clamp 19 are shown and described in the latter of the previously mentioned applications.

The upper clamp 18 is provided with an 35 annular socket plate 31, formed integral with the rear clamping band. The front band has a narrow strip of metal 32 joining the upper and lower parts of the band and this strip has a crowfoot formation engag- 40 ing over a wedge shaped projection on the rim of the socket plate 31 to hold the same to the insulator. The clamp 18 and socket 31 are designed to be universally adaptable to different insulators and to receive inter- 45 changeably different fittings, as shown and described in the patent application of Frank E. Getts, Serial No. 219,094, filed February 25, 1918.

The base 36 of the choke coil bracket 37 50 is bolted to the plate 31 by the bolts 38. Referring now to the detail views of the bracket, an upright 39 rises perpendicularly from the base 36 and branches off, at a point axially of the choke coil 41, into two 55 diverging arms 42 and 43. A wide rib 39' is cast integral with the base 36 and upright 39 to reinforce the latter. The diverging arms 42 and 43 are strengthened by ribs 42' and 43', which extend out to the end hub 60 portions 45 and 46. Each of these hub portions is provided with an angular depression 47 designed to cooperate with the removable clip 48 for clamping the choke coil wire therebetween. The circular depression 65 49 in the clip 48 and the angular depression

47 are curved concentrically with the curvature of the choke coils as shown in dotted lines in Fig. 3. The angular recess 47 secures effective clamping engagement with different gage wires. A screw 51 passes 70 through each clip 48 and a boss 52, cast in the rib 42; and threads into a nut 53.

Adjacent the base 36 the flaring web 54 is set back from the upright 39 to afford access to the angular depression 47'. The 75 screw bolt 51' threads into a boss 52' cast in the rib 39'.

The end turn of the choke coil 41 is first clamped in the lower depression 47'. For this operation the bracket is preferably free 80 so that it may be tilted back to afford access to the screw head 51'. The remainder of the end turn is then inserted and clamped under the other clips 48 by drawing up on the nuts 53.

Each end 55 of the coil are turned out for 85 connection to the line.

As shown in Fig. 2, spacing sticks 61 may be employed to prevent possible contact between adjacent turns and to add to 90 the rigidity of the coil. The sticks 61 form a non-yieldable connection between the two brackets 37, whereby line wire strains imparted to one end of the coil are transmitted through the coil and are borne by both 95 brackets and by the line wire on the other side of the coil.

These sticks are made of wood or other 100 insulating material and have grooves 62 in their opposing faces which engage over the turns of the coil. Screws 63 secure the sticks together.

The degree of tension on the choke coil 41 can be varied by shifting one or both of the insulator units, and furthermore, longer 105 or shorter coils can thus be accommodated. The universal clamps 18 and 19 are adaptable to insulators of different lengths, whereby the insulating capacity of the mounting can be easily increased by the substitution of insulators of greater capacity.

Obviously the mounting may occupy any 110 position. For inverted position, the petticoat insulators 17 are inverted on the mounting.

I do not intend to be limited to the particular details shown and described.

I claim:

1. In combination, a supporting member, a pair of insulator units on said supporting 120 member, each of said insulator units comprising a base member shiftable along said supporting member, an insulator mounted on said base member, a bracket mounted on said insulator, coil attaching means adapted 125 to hold a coil between the brackets of both insulator units, said insulator units being relatively shiftable along said supporting members to change the spacing between said brackets.

2. A bracket for supporting choke coils and the like comprising a base member, arms diverging from said base member, and releasable clip members attached to said arms 5 and to said base member, said clip members adapted to clamp to the choke coil.
3. A bracket for supporting choke coils and the like having a plurality of clip members attached thereto, and means coöperating with said clip members for releasably clamping said members to the choke coil.
4. A bracket for supporting choke coils and the like comprising a plurality of diverging arms, said arms having recesses 15 therein adapted to receive the end turn of the choke coil, and clip members coöperating with said recesses and adapted to clamp the choke coil wire in said recesses.
5. A bracket for supporting choke coils 20 and the like comprising a plurality of diverging arms, said arms having recesses therein adapted to receive the turn of the choke coil, removable clip members coöperating with said recesses and adapted to 25 clamp the choke coil wire in said recesses and screw means engaging said arms and
- operable to releasably clamp the clip members to the choke coil.
6. In combination, an insulator, a bracket for supporting choke coils and the like, said 30 bracket being mounted on said insulator, diverging arms on said bracket, and clamping devices on said arms adapted to clamp to the choke coil at different points of its circumference.
7. In combination, a pair of brackets, diverging arms extending from each of said brackets, clamping means on said arms, coil attaching means adapted to hold a coil between said brackets, and spacing members 40 adapted to engage with the ends of said choke coil between said diverging arms.
8. A bracket for supporting a choke coil or the like comprising a plurality of arms, and an attaching base common to the arms, 45 said base being adapted to be mounted on an insulated support, said arms having means at their outer ends for holding the end turn of a choke coil.

In witness whereof, I hereunto subscribe 50 my name this 26th day of April, A. D., 1918.

ERNEST H. JACOBS.
